G. CLAUSING

GOLF TEE

Filed March 19, 1927

INVENTOR
George Clausing
BY *Taulmin Taulmin*,
ATTORNEY

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

GOLF TEE.

Application filed March 19, 1927. Serial No. 176,809.

My invention relates to golf tees. It is the object of my invention to provide a golf tee having a plurality of ground engaging prongs and a plurality of ball engaging supports or prongs, so that a multiple point support will be provided for the tee, such points of support being separated to form a broad foundation for the tee.

It is a further object to provide a tee having a head with a plurality of spaced supporting points so that the ball will be suitably supported in position, but will have the minimum of engaging surface to impede its flight at the moment of departure from the surface or points of support of the tee.

Referring to the drawings:

Figure 1 is a plan view of the top of the tee showing the ball engaging portions;

Figure 2 is a side elevation of one form of reversible type of golf tee having a plurality of similar ball engaging and ground engaging portions;

Figure 3 is a side elevation embodying a plurality of spaced supports and spaced ball engaging supports;

Figure 4 is a top plan view of Figure 3;

Figure 5 is a bottom plan view of Figure 3;

Figure 6 is an enlarged end elevation of Figure 2.

Referring to the drawings in detail, 1 designates a central section from which taper on either side the ground engaging supports and the ball engaging supports. 2 designates generally the ball engaging supports which are preferably spaced at each of the four corners of the square intermediate body 1. Such supports may be square as shown in Figures 3 and 4 having their upper surfaces 3 cut on a plane parallel to the body surface planes and parallel to the ground plane or the points of support may be spaced at the four corners and consisting of sharpened points 4 as in Figure 1 and Figure 2.

The ground supporting fingers are located at the four corners of the body and consist of relatively long fingers relatively narrow in section designated 5 having sharpened points 6. It will be noted that the exterior surface of these ground engaging supports and the ball engaging supports substantially throughout the entire length thereof are parallel and at right angles to the upper and

lower faces of the body and at right angles to the ground surface. This facilitates the entrance into the ground of these fingers, and, due to the fact that there is a gradually decreasing area between the inner edges 7 of these fingers, the ground is crowded in 60 between the fingers so that a gripping action is formed between these fingers and the ground facilitating a very firm engagement of the tee with the turf. This is particularly 65 advantageous in inserting the tee in either turf or loose ground as it crowds the mass of the engaging earth in between these inwardly tapering fingers.

The form shown in Figures 1 and 2 and Figures 3, 4 and 5 are substantially identical 70 in essentials save that, for the purpose of convenience, the form in Figure 1 can support the ball on either end or engage the ground at either end.

In both instances, the ball is supported 75 upon the extreme four corners or points 8 providing the minimum of supporting surfaces for properly positioning the ball.

It will be understood that I desire to 80 comprehend within my invention such modifications as may be necessary to adapt it to varying conditions and uses.

Having thus fully described my invention, what I claim as new and desire to secure by Letters Patent, is:

1. In a golf tee, a body having a golf ball supporting portion and a plurality of relatively long ground penetrating fingers, said fingers being inwardly and upwardly tapered so that the ground may be crowded therebetween, the ends of said fingers being sharpened by being formed angularly downwardly and inwardly to a point.

2. In a golf tee, a body having a golf ball supporting portion and a plurality of relatively long ground penetrating fingers, said fingers being inwardly and upwardly tapered so that the ground may be crowded therebetween, the ends of said fingers being sharpened by being formed angularly downwardly and inwardly to a point, and the exterior of said fingers being formed parallel to one another.

3. In a golf tee, a square body, a plurality of square golf ball engaging portions mounted on the corners of said body having upper faces parallel to the upper face of the body, and a ground engaging portion on the other

- side of said body, said ground penetrating portion consisting of a plurality of spaced fingers mounted on the sides of said body.
4. In a golf tee, a square body, a plurality of square golf ball engaging portions mounted on the corners of said body having upper faces parallel to the upper face of the body, and a ground engaging portion on the other side of said body, said ground engaging portion consisting of a plurality of spaced fingers mounted on the sides of said body, at the four corners thereof.
5. In a golf tee, a square body, a plurality of square golf ball engaging portions mounted on the corners of said body having upper faces parallel to the upper face of the body, and a ground engaging portion on the other side of said body, said ground engaging portion consisting of a plurality of spaced fingers mounted on the sides of said body, at the four corners thereof, having exterior surfaces at right angles to the body surfaces and parallel to one another with upwardly and inwardly tapered inner surfaces.
6. In a golf tee, a square body, a plurality of square golf ball engaging portions mounted on the corners of said body having upper faces parallel to the upper face of the body, and a ground engaging portion on the other side of said body, said ground engaging portion consisting of a plurality of spaced fingers mounted on the sides of said body, at the four corners thereof, having exterior surfaces at right angles to the body surfaces and parallel to one another with upwardly and inwardly tapered inner surfaces, the extreme ends of said fingers being tapered inwardly and downwardly to form sharp points.
7. In a golf tee, an interchangeable tee consisting of a central square body, a plurality of oppositely disposed fingers, one on each corner of the body, the outer surfaces of which are parallel and the inner surfaces of which are tapered inwardly towards the body.
8. In a golf tee, an interchangeable tee consisting of a central square body, a plurality of oppositely disposed fingers, one on each corner of the body, the outer surfaces of which are parallel and the inner surfaces of which are tapered inwardly towards the body, the points of said fingers being sharpened by being bevelled inwardly towards the ends of the fingers.
9. In a golf tee, a body, ball supporting members, and relatively long, rigid ground penetrating prongs oppositely disposed on the said body, the said prongs being adapted to be used interchangeably for supporting the tee or supporting the ball.
10. In a golf tee, a body, ball supporting members, and relatively long and rigid ground penetrating prongs oppositely disposed on the said body, the said prongs being of the same size and form so that they can be used interchangeably for supporting the tee or supporting the ball.
11. In a golf tee, a body having a golf ball supporting portion, and a plurality of relatively long and rigid ground penetrating fingers oppositely disposed on said body and adapted to give a substantial penetration regardless of the hardness of the ground, the said fingers being adapted to be used interchangeably for supporting the tee or supporting the ball.
12. In a golf tee, a body having a golf ball supporting portion and a plurality of relatively long and rigid ground penetrating fingers oppositely disposed on said body, the said fingers being inwardly and upwardly tapered so that the ground may be crowded therebetween, the said fingers also affording a substantial penetration regardless of the hardness of the ground, the said fingers being adapted to be used interchangeably for supporting the tee or supporting the ball.

In testimony whereof, I affix my signature.

GEORGE CLAUSING.
